UNITED STATES PATENT OFFICE

MAURICE ROBBINS, OF BOSTON, MASSACHUSETTS

COLLAR

Application filed May 10, 1930. Serial No. 451,370.

An object of this, my present invention, is the provision of a shirt attached to a soft turn-down collar of such construction and arrangement as to assure the collar always retaining its upright condition and perfect shape, and which provides therewith a guide for the strap portion of a necktie so that the tie can be readily and conveniently passed through the collar and shield and artistically knotted without effecting the shape of the collar.

A still further object is to simplify and improve the collar construction upon which I was granted U. S. Letters Patent 1,691,856, 15 Nov. 13, 1928.

To the attainment of the foregoing and other objects which will present themselves as the nature of the invention is better understood, the improvement consists in certain other novel features of construction, combination and operative association of parts, satisfactory embodiments of which are disclosed by the accompanying drawings.

In the drawings:

Figure 1 is a perspective view of my improvement.

Figure 2 is a horizontal sectional view through the collar.

Figure 3 is a sectional view approximately on the line 3—3 of Figure 1.

Figure 4 is a sectional view approximately on the line 4—4 of Figure 1.

Figure 5 is a sectional view approximately on the line 5—5 of Figure 2.

Figure 6 is a plan view to illustrate a manner in which the collar and shield may be formed from a single strip of suitable fabric.

Figure 7 is a similar view but showing the collar and shield stitched together.

Figure 8 is a similar view showing the shield and neckband formed as a single unit.

Figure 9 is a similar view but showing the shield stitched to the neckband.

Figure 10 is a similar view showing the collar and neckband formed as a single unit.

Figure 11 is a similar view but showing the collar stitched to the neckband.

While in Figures 1 to 5 of the drawings I have illustrated the inner fold of the collar providing the shield of the improvement it

is obvious that the shield may be formed with the collar, as disclosed by Figure 8 of the drawings, may be attached thereto as disclosed by Figure 7 of the drawings or may be arranged between the folds of the collar, as disclosed by Figure 9 of the drawings. Also by reference to Figure 10 of the drawings it will be apparent that the collar may be integrally formed with the neckband of the shirt instead of stitched thereto as disclosed by Figures 1 to 6.

The shirt 1 has its front provided with the usual lapping portions, the outer element of which being in the nature of a pleat 2 and the inner lapping portion is provided with buttons to be received through button-holes in the pleat 2. To the neckband 3 of the shirt 1, in the construction as disclosed by said Figures 1 to 6 I stitch the lower edge of the outer fold 4 of the turn-over collar. The confronting ends or what is commonly termed the peaks are stitched to the shirt and to the neckband 3, as indicated by the characters 15 in Figure 1 of the drawings. Also the lower edge of the front of the collar is for a suitable distance, stitched to the shirt, as indicated in Figure 1 by the numeral 16. The collar is thus an integral part of the shirt and none of the outer portion or fold thereof can be separated from the shirt. The neckband 3 has stitched on the inner face thereof a fabric shield 5 which is arranged between the folds of the collar and stitched to the upper edge of the collar. The inner fold of the collar is indicated by the numeral 6, and the inner fold 7 is provided with lapping extended portions which are indicated for distinction by the numerals 7 and 8, respectively. The inner portion 7 is provided with a button 9 to be received through a button-hole in the outer lapping portion or end 8.

By reference to Figure 1 of the drawings it will be seen that the pleat 2 is cut from its outer edge at an angle to one of the upper and confronting ends of a collar and this angle portion is for distinction indicated by the numeral 10. Also by reference to Figure 1 it will be seen that the outer end of what I have termed the shield 5 is extended beyond the second end of the collar and is cut angu-

larly, as at 11, and that the lapping portions 7 and 8 connected by the button 9 are centrally received in the V-shaped opening afforded by the angle edges 10 and 11.

5 The shield 5, at the center of the rear thereof has preferably attached thereto a button 12 to be received through a button-hole 13 in the fold 6. This is, however, not an absolute requirement as there parts need 10 not be detachably connected. If desired, these parts may be tacked together by the usual threads.

The neck strap 14 of the scarf or tie is preferably arranged in the collar before the shirt 15 is arranged on the person of the user. One end of the strap 14 is inserted between, say the edge 11 of the shield and the rear or inner fold 6 of the collar and is trained through these portions of the collar and is passed be-

20 tween the angle portion 10 of the shirt so that both ends of the necktie will be thus brought through what I have termed a V-shaped opening afforded by the edges 10 and 11. When the button 12 is employed the same

25 is moved out of the button hole 13 to facilitate the application of the tie strap and thereafter fastened as are the buttons which connect the lapping front portions of the shirt and the button 9 is passed through the opening therefor, that is, after the shirt is applied on the person of the user. The tie may be then knotted in the usual manner.

From the foregoing description it will be noted that the neckband does not interfere 35 with the tie as the said tie is arranged above the neckband. It will be further seen that instead of the shirt and the shield being composed of two separate units, they can be made as a single unit and in this way reduce the 40 bulkiness on the top rim of the collar. Likewise the collar and neckband can be made as a single unit which is true with respect to the shield and neckband. Also if desired, the neckband can be extended so that the 45 collar will be integrally formed therewith, and it is believed that the construction and advantages of my present improvement will, when read in connection with the accompanying drawings, be apparent to those skilled in the art to which such invention relates and that further detailed description 50 will not be required.

Having described the invention, I claim:

1. A shirt having its front lapping and 55 the upper end of the outer pleat of the said lapping portion cut angularly, a turn-over collar whose folded edge is connected to the neckband of the shirt and whose outer fold has its lower edge stitched to the front of the 60 shirt and its confronting ends stitched to the front of the shirt and to the neckband, said neckband having opposite angle extensions, one of which alines with the angle end of the pleat, a fabric shield having its upper ends 65 stitched to the upper edge of the collar and

having extending ends to bridge the V-shaped space provided by the angle edges of the neckband, said ends designed to be arranged in lapping relation and a fastening element for said ends. 70

2. A shirt having its front lapping and the upper end of the outer pleat of the said lapping portion cut angularly, a turn-over collar whose folded edge is connected to the neckband of the shirt and whose outer fold 75 has its lower edge stitched to the front of the shirt and its confronting ends stitched to the shirt and to the neckband, said neckband having opposite angle extensions, one of which alines with the angle end of the pleat, a 80 fabric shield having its upper ends stitched to the upper edge of the collar and having extending ends to bridge the V-shaped space provided by the angle edges of the neckband, said ends designed to be arranged in lapping relation, a fastening element for said 85 ends and a fastening element between the rear of the collar and the shield.

In testimony whereof I affix my signature.
